(57) CLAIM

The ornamental design for a cosmetic container, as shown and described.

DESCRIPTION

FIG. 1 is a perspective view of a cosmetic container showing my new design;

FIG. 2 is a top plan view of the cosmetic container of FIG. 1;

FIG. 3 is a side view of the cosmetic container of FIG. 1; FIG. 4 is a bottom view of the cosmetic container of FIG. 1; and,

FIG. 5 is an end view of the cosmetic container of FIG. 1. Only one side view and one end view are provided, since the corresponding side and end views are mirror images. The markings, e.g., "F.L.A.T." shown in broken lines in FIGS. 1 and 2, are for illustrative purposes and forms no part of the claimed design.
